UNITED STATES PATENT OFFICE.

HENRY MALLEBRE, OF BALTIMORE, MARYLAND.

PIANO MUSIC-DESK.

SPECIFICATION forming part of Letters Patent No. 733,724, dated July 14, 1903.

Application filed April 10, 1903. Serial No. 151,978. (No model.)

To all whom it may concern:

Be it known that I, HENRY MALLEBRE, a citizen of the United States, residing at Baltimore, State of Maryland, have invented certain new and useful Improvements in Piano Music-Desks, of which the following is a specification.

My invention relates to improvements in piano music-desks, and particularly to that portion of the desk which supports the music.

The object of the invention is to provide an improved construction of hinging the support to the desk, whereby when the support is swung up and not in use the hinges by which the support is pivoted to the desk are hidden from view and the support will have the appearance of a molding.

Another object of the invention is to provide an improved device for operating the hinged support to lower the same.

The invention is illustrated in the accompanying drawings, in which—

Figure 1 is a perspective view of a portion of one end of a piano provided with my improved device, which latter is shown as in the closed position when not in use. Fig. 2 is a similar view of a piano and illustrates the desk in the inclined position and the improved support lowered and ready for use. Fig. 3 is an enlarged detail of a portion of the desk and support and illustrates the position of the parts when the support is closed. Fig. 4 is a similar view and illustrates the first step in operating the support to lower the latter; and Fig. 5 is a similar view, but shows the support in the lowered position.

In the drawings, A designates an ordinary piano-casing, which is provided at the front with the ordinary opening or recess a, in which latter the desk B is pivoted in any suitable manner. This desk performs the usual functions of desks and is adapted to be arranged in a vertical and also in an inclined position, and at the bottom the desk is provided with a longitudinal ledge b, which extends from one end of the desk to the other. This ledge b is provided on its upper side with a cavity c and on its lower side with a cavity d, and these two cavities are substantially in a vertical line with each other and are connected by a passage e. A stem f extends through said passage e and is provided at one

end with a head c', and at the other end said stem is provided with a button d'. The head c' is adapted to fit into the cavity c, while the button d' takes in the bottom cavity d.

One leaf, g', of a hinge g is secured to the top surface of the bottom ledge b and projects beyond the edge of said ledge, while the other leaf, g'', of said hinge is secured to the longitudinal supporting-strip h. This supporting-strip h is provided at one edge with a bead h', which projects substantially at right angles from the top surface of said strip when the latter is swung down.

It will be seen that in securing the hinge-leaf g'' to the supporting-strip the same is set back or away from the end h', so that said edge will project beyond the hinge and hide the same when the supporting-strip is swung up, as shown in Figs. 1 and 3. It will also be seen that when the supporting-strip is lowered, as in Fig. 5, the projecting end h' of the strip takes beneath the leaf g' of the hinge, and the latter serves as a stop and extra support to hold the supporting-strip in a horizontal position.

The operation is simple and as follows: Supposing the desk and supporting-strip to be closed and in the position shown in Figs. 1 and 3, in order to lower the supporting-strip or swing it down ready for use the operator will place the thumb beneath the button d' and push same upward, as illustrated by broken lines in Fig. 4. This operation will cause the stem f and head c' to move vertically, and during such movement the head c' will contact with the bead h' of the supporting-strip h and swing the latter away from the desk far enough to permit the fingers to grasp the same, as clearly illustrated in Fig. 4.

Having thus fully described my invention, what I claim as new, and desire to secure by Letters Patent, is—

1. A piano-desk having a bottom ledge, in combination with a supporting-strip pivoted with respect to said ledge and adapted to be swung over on top of the latter, and a stem movable vertically through said ledge for the purpose set forth.

2. A piano-desk having a projecting bottom ledge provided with cavities on opposite sides thereof in combination with a stem movable through said ledge and having a

- head and a button on opposite ends which take in said cavities, and a supporting-strip pivoted to said ledge and adapted to be folded over on top thereof and over said cavities.
- 5 3. A piano-desk having a bottom ledge in combination with a supporting-strip, and a hinge, one leaf of which is secured to the top surface of said bottom ledge and projects beyond the edge thereof and the other leaf of
- 10 said hinge being secured to said supporting-strip and set back or away from its edge

whereby when the supporting-strip is folded over on top of the bottom ledge one end of the strip will project beyond and cover the hinge.

15

In testimony whereof I affix my signature in the presence of two witnesses.

HENRY MALLEBRE.
